UNITED STATES PATENT OFFICE

WILBUR TEALE AND HERBERT F. MC LAUTHLIN, OF SEATTLE, WASHINGTON, ASSIGNEES TO HYDRO-OIL FIRE CORPORATION, OF TACOMA, WASHINGTON, A CORPORATION OF WASHINGTON

HYDROOIL BURNER

Application filed January 19, 1926. Serial No. 82,191.

The invention is an oil burning system that mixes comparatively cold water either fresh or salt, with the oil, then mixes the oil and water with air at two consecutive 5 points, during which time the water is broken into small particles and the small particles of water are coated with oil, and then discharged through an open pipe against an upwardly inclined curved baffle of special metal, 10 and which is heated to a high temperature.

It is an object of the invention to provide a means for burning oil fuels which will make it possible to burn absolutely all of the oil leaving no residue such as asphaltum, tar or 15 carbon deposits in the fire box.

Another object of the invention is to provide a burner in which the actual ignition is deterred until chemical action, resulting from the contact of the mixture with a heated 20 surface, has taken place.

Another object of the invention is to provide a burner in which all dangers of flare back in lighting or relighting are eliminated.

Another object of the invention is to provide 25 an oil burning system which is so arranged so that the fuel is discharged to the fire through the open end of a comparatively large pipe under comparatively low pressure to insure against noisy operation.

Another object of the invention is to provide 30 a burner using either fresh or salt water with oil and air and brought in contact with a special metal or catalytic agent.

A further object of the invention is to provide 35 an oil burning system in which the oil coated particles of water strike a heated metal deflector which causes the water to burst into steam disrupting the oil coating which produces an atomization of this oil that 40 cannot be equaled in any other manner.

A still further object of the invention is to provide 45 an oil burning system which has both preliminary and final combustion areas in which the ingredients are changed chemically and physically in the first or incomplete

combustion area and then the balance of combustible elements completely oxidized, ignited and thoroughly burned in the second or final combustion area.

With these ends in view the invention embodies a blower in which the discharge pipe 50 passes comparatively straight into a fire box, a triple control valve for controlling the proportionate amounts of air, oil and water, respectively, an air connection between the blower and said valve, other connections 55 from the said valve to the said former discharge pipe of the blower, and to air and oil supply tanks, and a burner comprising an upwardly inclined curved plate.

Other features and advantages of the invention will appear from the following description taken in connection with the drawings, wherein:—

Figure 1 is a side elevation showing the arrangement of the system. 65

Figure 2 is a detail showing a cross section through the triple control valve.

Figure 3 is a detail showing the point at which the oil, air and water enter the blower 70 discharge pipe.

Figure 4 is a cross section on line 4—4 of Figure 3 showing a semi-circular plate forming a baffle upon which the oil, air and water will strike. 75

Figure 5 is a detail showing the baffle plate in the combustion chamber.

Figure 6 is a cross section through the baffle plate looking toward the hub of the plate showing a semi-circular plate projecting at 80 the discharge opening.

In the drawings we have shown our device as it would be made wherein numeral 1 indicates the blower, numeral 2 the triple control valve and numeral 3 the burner. 85

The blower 1 may be of any suitable type or design and may be provided with a discharge pipe 4 which will extend from its discharge opening to the burner 3. Another pipe 5 extends from the discharge of the 90

pump to the valve 2 and then passes from the valve to a fitting 6 into which it extends as shown in Figure 3. It will be noted that the lower end of the small pipe is cut as shown at the point 7 and directly below the lower end 5 is a baffle plate 8 upon which the mixture passing through the tube will drop as it leaves the tube. It will be observed that the mixture will then be carried through the pipe 4 to the burner.

10 The valve 2 is made as shown in Figure 2 with an outer casing 9 and a core 10 which has a stem 11 having a handle 12 at the outer end by which it may be rotated. The outer casing 15 is provided with bosses 13 and 14 into which the pipe 5 is screwed and other bosses 15 and 16 into which the oil and water pipes are screwed. The core 10 is provided with a web 17 which forms an upper compartment 20 and a lower compartment, and the outer wall of the upper compartment is provided with a plurality of openings 18 which are of different sizes so that by bringing different openings in positions to correspond with the openings in the bosses 13 and 14 different amounts 25 of air may pass through the valve; and at the same time different amounts of oil and water will be admitted to the lower compartment through openings 19 and 20 which will correspond with openings in the bosses 15 and 16. The size of these openings will be so arranged 30 that as the core is rotated, predetermined proportionate amounts of air, oil and water may pass through the valve and to the burner. 35 In the design shown the oil is admitted through the pipe 21 which may be connected to a tank or any suitable means for supplying oil and the pipe 22 may be connected to a water tap or any suitable means for supplying water at atmospheric temperature. The lower end of the lower compartment of the valve into which the oil and water pass is provided with an opening 23 at the bottom which permits the oil and water to pass down 40 through a pipe 24, and the pipe 24 is connected to and extends into the air pipe 5, thereby forming a jet, and it will be seen that as the air passes through the pipe 5 it will draw in the oil and water and thereby break the 45 water up into fine particles, which will become coated with oil. These particles pass downward through the pipe 5 and are injected against the plate 8 in the pipe 4 where any free water is broken and coated with oil and carried from this point into the burner 3.

50 The burner 3, which is shown in Figures 5 and 6, is provided with a hub 26 and an upwardly inclined curved plate 27. The pipe 4 is threaded into one end of the hub and the other end is provided with a semi-circular plate 28 which extends outward beyond the hub and is held in the upper part of the opening. It will be noted that plate 28 is made of comparatively thin metal or plate 55 and the particles of oil and water with air

pass under it getting the third preparation for the first and second stages of actual combustion. It further provides a means for starting combustion quickly, such as in lighting the fire, as being thin it heats quickly 70 and starts volatilization which in turn heats the plate 27 to the required temperature. It will be noted that as the plate 27 is in the fire box it will become heated and as the particles of water and oil roll out and upon it 75 they will receive their final preparation for combustion.

It will be understood that changes may be made in the construction without departing from the spirit of the invention.

80 The construction will be readily understood from the foregoing description. To use the device it may be set up as shown, and it will be observed that as the blower 1 is started a current of air will pass through the pipe 4 to the burner 3 and another current of air will pass through the pipe 5, the valve 2 and the fitting 6 to the pipe 4 and then to the burner. It will be observed that the pipe 5 is provided with long radius bends 85 forming easy curves so that the air passing through the pipe 5 will retain a comparative constant velocity. The velocity of the air in the pipe 5 will facilitate the jet at the point 25 and at the same time cause the mixture to be injected into the pipe 4 through the fitting 6 so that it will be thoroughly broken up before it is discharged against the freely exposed plate 27. The mixture is not discharged through a jet or even a small opening, but is permitted to flow out of the open end of the pipe so that all tendency to clog or become obstructed through carbon deposit on or in the jet or orifice will be eliminated. The large opening permits the use of a low 90 velocity and a low pressure, thereby tending to reduce noise to a minimum. As the mixture flows out along the heated plate it receives its final preparation for combustion and undergoes initial combustion. This action will start at the point A and from this 95 point the mixture will pass to the point B where complete combustion will start. This combustion will extend through the combustion chamber and burn absolutely all of the 100 mixture leaving no residue.

110 Having thus fully described the invention, what we claim as new and desire to secure by Letters Patent, is:—

115 1. In an oil burning apparatus, a furnace, an air main leading to said furnace, a by-pass air pipe leading from said main and reentering said main ahead of the furnace, a triple valve in said by-pass pipe, an oil supply pipe and a water supply pipe leading into said by-pass pipe through said valve whereby said valve controls the supply of oil and water to the air, and a mixing baffle in said main where the by-pass pipe reenters said main.

2. In an oil-burning apparatus, a furnace, a main air pipe to said furnace, a secondary air pipe discharging into said main air pipe, a triple valve in said secondary air pipe, an oil supply pipe and a water supply pipe leading into said secondary air pipe through said valve whereby to control the relative proportions of the oil and water supplied to the air therein, and fluid mixing means where said secondary air pipe enters said main pipe.

10 In testimony whereof we affix our signatures.

WILBUR TEALE.
